CLOCKCASE CONSTRUCTION

Everett M. Patterson, Watertown, Conn., and William Klein, Forest Hills, N. Y., assignors to The United States Time Corporation, Waterbury, Conn., a corporation of Connecticut

Application July 3, 1946, Serial No. 681,362

2 Claims. (Cl. 58—54)

1

This invention relates in general to clock structures and is more particularly concerned with the outer casing which houses the movement of the clock.

It has been the practice in the past to make clock cases in two parts which are telescoped together and held in place by screws or bolts. This practice required that holes be provided in the telescoping parts of the clock case, and it was necessary that these holes be aligned before the screws or bolts could be put into place. In the case of a round clock, it was often somewhat difficult to properly align these holes. Furthermore, the heads of the screws or bolts which held the two parts of the clock case together protruded from the outside of the case making an unsightly and sometimes unsymmetrical appearance.

It is the object of this invention to provide a clock case having two parts which are held together without any visible screws or bolts.

It is a further object of this invention to provide a clock case which may be easily and readily assembled without the use of visible screws or bolts, and at the same time provide a means whereby the two parts of the casing may be readily taken apart for purposes of cleaning or otherwise.

Referring now to the drawing for a complete disclosure of one specific embodiment of the invention.

Fig. 1 is an exploded view of the clock of the present invention.

Fig. 2 is a detail view of part of the means for securing the two parts of the casing together.

Fig. 3 is a detail of another part of the fastening means.

Fig. 4 is a view of the assembled clock in the process of being disassembled.

Referring now to Fig. 1, the movement of the clock is indicated generally at 2 with the usual pillars being indicated at 4. The movement cover of the clock is shown at 6 and, as seen in Fig. 1, the movement 2 is secured within the movement cover 6 by having the pillars 4 extend through openings 8 in the back of the movement cover. Rubber grommets are provided in the opening 8 to lessen the vibration transmitted by the movements to the movement cover 6. Nuts 10 are provided to secure the pillars 4 firmly to the movement cover 6.

The particular clock chosen for illustration is an alarm clock and the clapper is indicated in Fig. 1 at 12 extending through an opening 14 in the movement cover. While the clock shown for

purposes of illustration is an alarm clock, this particular invention is equally applicable to other types of clocks. If the clock did not have an alarm, the opening 14 would, of course, not be provided in the movement cover 6 and the movement cover would be the back of the clock. Under these circumstances, however, the shape of the movement cover would probably be different from here shown to present a more attractive appearance.

The movement cover 6 is provided around its outer edge with a flange 16 having notches 18 cut therein at two points, one near either side of the top of the clock for a purpose to be presently described. The flange 16 is also provided with two small holes 20 near the bottom thereof.

The alarm bell 22 is provided on its inner side with a bracket 24 spot welded to the bell at 26. The bracket 24 is provided with a plurality of ears 28 which extend through openings or slots provided therefore in the movement cover 6. After the ears 28 are extended through the slots in the movement cover, they are twisted so that the bell 22 will be firmly attached to the movement cover 6. The bracket 24 is provided with openings 30 which in assembled condition of the clock receive the nuts 10 and ends of the pillars 4. Thus it will be seen that no screws, studs, or bolts are visible when the clock is viewed from the back, other than the necessary control and winding knobs.

The crystal of the clock is indicated at 32 and is held in place by the bezel 34. The bezel 34 is provided with a flange 36 which in assembled condition of the clock telescopes snugly around the flange 16 of the movement cover 6. The flange 36 is provided with indentations 38. When the movement cover 6 and the bezel 34 are fitted together, the indentations 38 will snap into the notches 18 cut into the flange 16 of the movement case and hold the two members in assembled condition. In order that the clock may be taken apart for cleaning or other purposes, a notch 40 is provided in the flange 36 of the bezel, leaving a space 42 between the bottom of the notch 40 and the flange 16 of the movement cover 6 into which an instrument, such as a screwdriver 44, may be inserted to pry the bezel and the movement cover apart. From Fig. 1, it is evident the notch 40 is placed in the flange 36 centrally of the bottom portion thereof. As seen in Figure 3, an opening 46 is provided in the flange 36 closely adjacent either side of the notch 40.

The particular clock illustrated is round and the base 48 is made of such configuration as to

conform closely to a portion of the periphery of the clock. The base 48 is provided with a pair of holes 50 which are adapted to receive screws 52.

Exclusive of the bell, which as previously stated may be eliminated in some instances, the clock is assembled in a manner which will now be described. The pillars 4 of the movement are extended through the holes 8 in the back of the movement cover and the nuts 10 are then screwed on the ends of the pillars to hold the movement and the movement cover together. The flange 36 of the bezel 34 is then placed around the flange 16 of the movement cover and the two members are squeezed together until the indentations 38 snap into the notches 18 in a manner which will readily be understood. At this time, the holes 20 in the flange 16 of the movement cover will be aligned with the openings 46 in the flange 36 of the bezel as seen in Fig. 3. It will here be noted that the openings 46 are elongated and that the notches 18 are also elongated so that the bezel 34 and movement cover 6 may be secured together without requiring the various fastening means be perfectly aligned as has been customary in the past in structures wherein circular screw holes were used. After the bezel 34 and the movement cover 6 have thus been secured together, the base 48, which has a concave seat 49 therefore, receives the case in such manner as to completely cover the notch 40 and slot 42 between the flange 36 of the bezel and the movement cover 6. The holes 50 are then readily aligned perfectly with the holes 20 in the flange 16 and the screws 52 are then passed through the openings 50 in the base and the openings 46 in the flange of the bezel and are screwed into the holes 20 in the flange of the movement cover 6 thus holding the two parts of the casing and the base in assembled position. In the particular construction shown, the screws 52 are of the self-tapping variety and the holes 20 in the flange 16 are not threaded, though it will readily be appreciated that other types of screws may be used and the holes 20 may be threaded if desired without departing from the spirit of the invention.

Thus it will be seen that a clock case has been provided which is held together by the two indentations 38 and the two screws 52. The screws which hold the two parts of the casing together are not visible when the clock is in the normal position and are only accessible from underneath the base of the clock. The only visible means for securing the two parts of the casing together are the indentations 38 which are inconspicuously small, do not protrude outwardly from the periphery of the case, and do not detract from the beauty and symmetry of the clock.

While the invention has been illustrated and described in its preferred embodiment and has included certain details, it should be understood that the invention is not to be limited to the precise details herein illustrated and described since the same may be carried out in other ways, falling within the scope of the invention as claimed.

What we claim is:

1. A clock case comprising a movement cover having a flange around the edge thereof and a bezel having a flange telescoping over the flange of said movement cover, a plurality of interengaging means on said flanges to hold said movement cover and said bezel in telescoping relation, said means being spaced from each other and positioned in the upper portion of said case, a notch in the lower portion of the flange of said bezel cut inward to such an extent that a space is provided into which an instrument may be inserted between the base of the notch and the flange of the movement cover to pry said movement cover and said bezel apart; in combination with a base for said clock case, and screws connecting said base to the lower portion of the bezel and the flange of said movement cover, said bezel and base and movement cover flange having aligned openings to receive said screws.

2. A case for a substantially round clock comprising a movement cover having a circular flange around the edge thereof and a bezel having a circular flange telescoping over the flange of said movement cover, a plurality of interengaging means on said flanges positioned in the upper portion of said flanges and spaced from each other to hold said movement cover and said bezel in telescoping relation, the flange of said bezel having a notch in the bottom portion thereof cut inward to such an extent that a space is provided into which an instrument may be inserted between the base of the notch and the flange of the movement cover to pry said movement cover and said bezel apart, said flange of the bezel also having an opening therein adjacent each side of said notch; in combination with a base for said clock case, said base being of such shape as to generally conform to the bottom of the bezel and completely cover the notch in the flange of said bezel and having a pair of screw receiving openings therein juxtaposed the openings in the flange of said bezel, and a pair of screws extending through the openings in the base and in the flange of the bezel and screwing tightly into the flange of said movement cover to maintain said case parts and base assembled.
